(57) **CLAIM**

The ornamental design for a positioning tool for punching, as shown and described.

DESCRIPTION

FIG. 1 is a perspective view of a positioning tool for punching showing my new design;
FIG. 2 is another perspective view thereof;
FIG. 3 is a front elevational view thereof;
FIG. 4 is a rear elevational view thereof;
FIG. 5 is a left side elevational view thereof;
FIG. 6 is a right side elevational view thereof;
FIG. 7 is a top plan view thereof;
FIG. 8 is a bottom plan view thereof; and,
FIG. 9 is an exploded perspective view of the positioning tool for punching.

The broken lines in the drawings depict portions of the positioning tool for punching that form no part of the claimed design.
